G. HALINKA

DOOR LATCH

Filed April 24, 1925

Patented Oct. 27, 1925.

1,558,980

UNITED STATES PATENT OFFICE.

GEORGE HALINKA, OF DETROIT, MICHIGAN.

DOOR LATCH.

Application filed April 24, 1925. Serial No. 25,507.

To all whom it may concern:

Be it known that I, GEORGE HALINKA, a citizen of the United States, and residing at Detroit, county of Wayne, and State of Michigan, have invented a new and Improved Door Latch, of which the following is a specification.

This invention relates to door latches, and relates more particularly to latches dependent upon push and pull members for actuation.

It is an object of the invention to provide a door latch that will present a neat appearance when applied on a door, and to further provide means for operating the latch member by a pulling stress applied to a pull member on one side of the door, or a pushing stress applied to a push member arranged on the opposite side of the door.

It is another object of the invention to provide means whereby the pull member may be securely locked from movement and at the same time permit free movement of the latch member by actuation of the push member.

A further object is to provide means actuating a latch member by movement of either the push or pull member, each independently of the other.

The above and other objects will be apparent from the following description wherein reference is made to the accompanying drawings illustrating a preferred embodiment of my invention.

In the drawings:

Figure 1 is a fragmentary view of a door and door jamb with the invention attached thereto.

Figure 2 is a cross sectional view, taken upon the line 2—2 of Figure 1, and shows more particularly the means for operating the latch member by the mechanism provided with the push member.

Figure 3 is a cross sectional view, taken on the line 3—3 of Figure 1 and shows more particularly the operating mechanism for actuating the latch member by the mechanism provided with the pull member, and also discloses means for locking the pull member from movement.

Figure 4 is a cross sectional view, showing how the pull member may be locked from movement from the interior of the door, instead of using a key lock as shown more particularly in Figure 3.

In these views, the reference character 1 designates a fragmentary portion of a door jamb and 2 the fragmentary portion of a door. The invention comprises a metal plate 3 provided with an opening 4 for receiving a latch member, said plate being held firmly in position by screws 5. A latch member 6 is slidably mounted in a frame 7 which is securely attached to the door by screws 8. Arranged on a cylindrical projection 9 of the latch member 6 is a coiled spring 10 urging said latch member toward the door jamb.

Referring now more particularly to Figure 2, the means for actuating the latch member 6 from one side of the door comprises a latch dog 11 adapted to coact with the projecting lug 11^A of the latch member 6. Said latch dog 11 is pivotally mounted by a pin 12 on a lug 13, integral with a housing 14 which is attached to the door by screws 15. Within said housing 14 there is provided a cylindrical opening 16 and a reduced opening 16^A. Disposed within the cylindrical opening 16 there is a push member 17 formed with a large end to slidably engage the walls of the opening 16 and having a smaller end projecting through the reduced opening 16^A for engagement with the latch dog 11. The push member 17 is urged outwardly by a spring 18 and is prevented from complete disengagement by a pin 19.

Referring now more particularly to Figure 3, the means for actuating the latch member 6 from the other side of the door, comprises a pull member 20 of substantially cup-shape, having an integral flange 20^A for use as a grip member. The pull member 20 is further provided with an integral cam shaped lug 21 projecting inwardly and terminating in a lug 21^A, disposed at substantially a right angle to the face of the cam, which is adapted to slidably engage the projecting lug 21^B of the latch member 6. Said pull member 20 is hingedly mounted on lugs 23 integral with a casing 24, which is formed to substantially meet the contour of the surface of the pull member 20, and is securely held in a mortised portion in the door by screws 25. Said casing 24 is also provided with an integral lug 26 to which is attached one end of a spring 27, the other end of said spring being attached to the cam shaped lug 21. Said spring thus serves to resiliently hold the pull member 20 sub-

stantially within the concaved portion of the casing 24, and also to return said pull member to its normal position after it has been stressed outward as shown in dotted lines.

5 To lock the pull member 20 from movement there is provided a tumbler or other suitable lock 28, said lock having an arm 29 projecting therefrom for engagement with registered slots 30 and 30^A provided in the casing 24 and in the pull member 20.

10 In Figure 4 of the drawing there is disclosed an alternative means for locking the pull member 20 from movement, said means comprising a bolt 31 having an integral projecting lug 32 for engagement with the registered slots 30 and 30^A, said bolt 31 being actuatable by a thumb lever 33 attached thereto by a screw 34.

15 20 The latter disclosed locking means is preferably on all except one door, where hardware of this character is used on automobiles, as all doors except one may be locked from the interior of the car, thus eliminating 25 the necessity of using a key, except for one door.

20 It is to be noted that the means provided on either side of the door for actuating the latch member 6 are wholly independent of each other and further would permit opening of the door from the push member side, even though it be locked from intrusion from the pull member side.

30 35 It is thought that the device is of sufficiently simple nature that no description as to how it operates in use may be required.

40 From the foregoing description it becomes evident that the device is of simple nature, will not easily get out of order and provides means for accomplishing the objects described.

45 While it will be apparent that the illustrated embodiment of my invention herein disclosed is well calculated to adequately fulfill the objects and advantages primarily stated, it is to be understood that the invention is susceptible to variation, modification

and change within the spirit and scope of the subjoined claims.

Having thus described my invention, I 50 claim:

1. A door latch comprising a frame, a latch member slidably mounted therein, a push member and a pull member and means actuating said latch member by actuation of 55 the push or pull member independently.

2. In a device of the character described, comprising a latch member, a frame for slidably mounting said latch member, a push member and a pull member for actuating 60 said latch member, and means locking said pull member against actuation.

3. In a device of the character described, comprising a latch member, means slidably mounting said latch member on a door, 65 independent means actuating said latch member by a pushing stress applied from one side of said door, and further independent means actuating said latch member by a pulling stress applied from the opposite 70 side of said door.

4. In a device of the character described, comprising a latch member slidably mounted on a door and adapted to be actuated by a push member or pull member independently, 75 means locking one of said actuating members and still permit free movement of the other of said actuating members.

5. In a device of the character described comprising a frame, a spring pressed latch member slidably mounted therein, a latch dog coacting with said latch member, a push member slidably mounted within a housing and adapted to coact with said latch dog, a pull member hingedly mounted and having an integral cam faced lug slidably engaging 85 said latch member, a casing for housing said pull member and means resiliently holding said pull member normally within said casing. 90

In witness whereof I hereunto set my hand.

GEORGE HALINKA.
